UNITED STATES PATENT OFFICE.

LILLIAN F. VAN TINE, OF PHILADELPHIA, PENNSYLVANIA.

MUSIC-CHART.

1,258,832.

Specification of Letters Patent. Patented Mar. 12, 1918.

Application filed April 12, 1917. Serial No. 161,392.

To all whom it may concern:

Be it known that I, LILLIAN F. VAN TINE, a citizen of the United States, residing in the city and county of Philadelphia, 5 State of Pennsylvania, have invented a new and useful Music-Chart, of which the following is a specification.

The object of my present invention is to provide a staff in which the different lines 0 have different colors on one side of the music chart, while the lines on the other side of the chart are all of a single color, and in connection with such chart, I employ colored markers and finger pieces which correspond in color to the lines of the staff.

With the above and other objects in view which will hereinafter more clearly appear in the detailed description, my invention consists of a novel music chart.

It further consists of other novel features of construction and advantage, all as will hereinafter more fully appear.

For the purpose of illustrating my invention, I have shown in the accompanying drawings a typical embodiment thereof, which is at present preferred by me, since this embodiment will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a face view of a music chart embodying my invention.

Fig. 2 represents a plan view of the colored side of certain disks employed.

Fig. 3 represents a plan view of the disks, showing the opposite side of that seen in Fig. 2.

Fig. 4 represents a plan view of the back of the music chart.

Fig. 5 represents a plan view of the front face of a music chart, with a different clef from that seen in Fig. 1.

Fig. 6 represents a plan view of certain other disks employed.

Fig. 7 represents a side elevation of finger pieces employed.

Fig. 8 represents a plan view of the rear face of the music chart shown in Fig. 5.

Similar numerals of reference indicate 55 corresponding parts in the figures.

Referring to the drawings:—

Referring first to Figs. 1 and 4, 1 designates the music chart, on the front face of which is indicated the staff 2 and the treble clef 3. The lines of the staff are indicated 60 in different colors, and for purposes of illustration, I have shown the first line as being red, the second line as being green, the third line as being purple, the fourth line as being yellow, and the fifth line as being blue. The 65 degrees of the staff have letters placed thereon indicative of the notes. I have also shown one leger line, which is indicated in black and has placed thereon the letter C. The first space below the regular staff has 70 placed thereon the letter D and the first space above the regular staff has placed thereon the letter G.

4 designates markers or disks, one face of which is colored to correspond to the color 75 of a line of the staff and the other face of each disk is marked with a letter indicative of each line of the staff. On the back of the music chart is placed a staff 5 in which the lines are all printed in the same color, such 80 as for example, black, and the treble clef 6 is indicated on the staff.

In Figs. 5 and 6 I have shown a music chart having a staff thereon indicative of the bass clef. The front face of this sheet 85 of the music chart has a staff 7 indicated thereon and the bass clef 8. The lines are colored so that each line of the staff has its own special color. The lower leger line is indicated, for example, in red. The first 90 line of the staff is indicated in green, the second line of the staff is indicated in purple, the third line of the staff is indicated in yellow, the fourth line of the staff is indicated in blue, and the fifth line of the staff is indicated in pink. It will thus be understood that the lines of the treble and bass clefs which correspond to the same note are indicated in the same color.

9 designates disks which form markers, 100 one face of these disks being white and the other face of these disks having indicated thereon letters corresponding to the notes of the spaces. 10 designates finger pieces comprising strips of colored material secured 105 together in ring formation so that they can be slipped on the fingers of the hand. These rings are colored to correspond to the colors of the degrees of the staff.

The rear face of the sheet of the music 110

chart indicative of the bass clef is provided with a staff 11, the lines of which are all of the same color, for example, black. The bass clef 12 is indicated on the staff 11. It 5 will thus be seen that I provide a sheet for each clef.

In using the chart, the colors are first taught to the student in the order in which they appear on the chart. The disks 4 are 10 then placed on the corresponding colors covering the letters and with the color side up. The letters in the spaces are covered with the disks 9, using at first the four disks which spell "face" and arranging them with 15 their unlettered sides uppermost. When these are thoroughly known, the disks G and B are added. Now one after the other, the disks are turned letter side up, retaining them on the proper line or space and naming them aloud. The disks are then turned 20 to make their unlettered sides uppermost and the disks are placed so as to cover the letters, and the student then is asked to name the lines and spaces without seeing the 25 letters. After the student is able to do this accurately with the colored lines, the sheet of the music chart is turned over, and the colored disks are placed on the proper lines and spaces and identified by the student. 30 After the colors have become associated in the mind of the student with the names of the lines, the use of the disks 4 is gradually discarded and disks 9 are used on the black lines, these disks having letters printed on 35 one side and having their other side white. The student soon becomes able to print letters or notes on the staff, calling them by name without hesitation.

The chart can be used as a game by two 40 children, by dividing the disks evenly between them and letting them take turns in placing them correctly. The rings 10 are placed on the student's fingers in the order of the chart colors, placing the hand horizontally along the lines and naming the line. The hand with the rings on is placed on 45 the corresponding keys on the piano, naming the keys as this is done. The rings may be slipped from the fingers and placed on 50 the corresponding keys. This brings the chart work to the piano and locates the lines and spaces on the key-board.

It will be apparent that by employing the

music chart herein disclosed and carrying out the steps of the method as herein defined, the student soon becomes familiar with the positions of the notes with relation to the lines and spaces of the staff. The disks 55 form markers which conceal the letters indicated on the staff.

It will now be apparent that I have devised a novel and useful music chart, which embodies the features of advantage enumerated as desirable in the statement of the invention and the above description, and 60 while I have, in the present instance, shown and described a typical embodiment thereof which will give in practice satisfactory and reliable results, it is to be understood that this embodiment is susceptible of modification in various particulars without departing from the spirit or scope of the invention or sacrificing any of its advantages.

Having thus described my invention, what I claim as new and desire to secure by Letters Patent is:—

1. An apparatus for teaching music, comprising a chart bearing on its face a staff the lines of which are of different colors, and the lines and spaces of which bear their respective letters, and markers constructed and arranged for removable arrangement on the staff and of a size to cover and hide the letters of the staff, each marker having one side colored correspondingly to one line of 80 the staff and being provided on its opposite side with the respective letter of said line.

2. An apparatus for teaching music, comprising a chart bearing on its face a staff the lines of which are of different colors, 90 and the lines and spaces of which bear their respective letters, with the letters spaced apart and those complementary to the lines arranged in a separate series from those complementary to the spaces, and markers 95 constructed and arranged for removable arrangement on the staff and of a size to cover and hide the letters of the staff, each marker having one side colored correspondingly to one line of the staff and being provided on 100 its opposite side with the respective letter of said line.

LILLIAN F. VAN TINE.
